UNITED STATES PATENT OFFICE.

NICHOLAS CARMAN, OF SPRINGFIELD, OHIO.

DESIGN FOR A BADGE.

SPECIFICATION forming part of Design No. 17,679, dated September 6, 1887.

Application filed May 10, 1887. Serial No. 237,773. Term of patent 3½ years.

To all whom it may concern:

Be it known that I, NICHOLAS CARMAN, a citizen of the United States, residing at Springfield, in the county of Clark, State of Ohio, have invented and produced a new and original Design for Badges or Charms, of which the following is a specification, reference being had to the accompanying drawings, forming part thereof.

10 Figure 1 is a view looking at one face of my newly-designed badge or charm, and Fig. 2 a view looking at the other face thereof.

My design is double sided or faced, and it consists of three triangular plates, A, arranged 15 approximately equidistantly apart, and having ornamental borders at the edges thereof and on both sides, as seen in both figures.

On the side represented in Fig. 1 two overlapping triangles or triangular plates, B and C, 20 are placed upon the adjacent corners of the plates A, and are ornamented with any suitable border. Represented upon these triangles B and C is a lily, while encircling said triangles and resting upon the triangles A is a 25 ring or circular band, D, suitably ornamented. Outside of said band, and running from one of the plates A to each of the other plates A, are portions E' of a wreath. The triangle B passes behind the triangle C in Fig. 2, and the latter 30 triangle in said figure bears the representations of a skeleton-head with crossed bones beneath it in one corner, and in the other a book resting upon a pedestal and having letters thereon and two swords crossed about the 35 book, while near the lower corner is the rep-

resentation of an open book with a sword laid across it. Cross-sabers E appear upon both sides, being the same sabers. Mounted upon the upper plate, A, is an ornament, F, and a helmet and visor, G and H, with an eagle 40 standing on the helmet and having several links extending from it.

The principal features of my design are the outer triangles, the band upon them, and the overlapping triangles resting upon the corners 45 of the outer triangles and encircled by the band, and suitable inscriptions and ornaments upon the several features.

I claim—

1. The design for badges or charms herein 50 shown and described, the same consisting of the three triangles A A A, the two triangles B C, and of a band, D.

2. The design for badges or charms herein 55 shown and described, consisting of the triangles A A A, the circular band D, portions of a wreath extending between the triangles A A, crossed sabers E, a superimposed helmet, G, a visor, H, and an eagle, the triangles B C having a representation of a lily on them at 60 one side of the badge or charm and the representations shown on the triangle C at the other side.

In testimony whereof I affix my signature in presence of two witnesses.

NICHOLAS CARMAN.

Witnesses:

WILBER COLVIN,
A. A. YEATMAN.
